UNITED STATES PATENT OFFICE

FRANK F. FORSHEE AND FRANK THORNTON, OF MANSFIELD, OHIO, ASSIGNORS TO
WESTINGHOUSE ELECTRIC & MANUFACTURING COMPANY, A CORPORATION OF
PENNSYLVANIA

ELECTRIC IRON

Application filed December 29, 1925, Serial No. 78,101. Renewed October 26, 1928.

Our invention relates to electric heating devices and particularly to electrically heated flat irons.

An object of our invention is to provide a flat iron that shall have its heating element embedded in its top plate.

Another object of our invention is to provide a flat iron that shall have associated therewith, a heating unit which is easily manufactured, readily located in its operative position within the flat iron, and which will have long life.

Heretofore, the usual heater employed in electrically heated flat irons comprised a strip of mica, around which was wound a conductor of high resistance material. The resistor was disposed in a metallic sheath from which it was suitably insulated by strips of mica. Heat transfer from the heating element to the sole plate of the flat iron has been effected by a pressure clamp or weight member that was secured above the heating element.

With this type of construction, the heating elements were subjected to very high temperatures because of the relatively low thermal conductivity of mica and the resulting temperature drops between the element and the mica and between the mica and the sole plate.

In accordance with our invention, we have provided a heating unit which comprises an electric resistance conductor and an oxidizable tube or sheath which encloses the conductor and is located in a cast iron member. By subjecting the tube enclosing the resistor to a gaseous atmosphere of suitable oxygen content, the oxidizable metal is changed to an oxide thereof, and simultaneously expands sufficiently to cause a compact and efficient heat path to exist between the electrical conductor and the cast iron member. Since the resistor is in good thermal contact with the iron member, it will operate at a much lower temperature than is the case when the elements are insulated by mica; therefore, the heating element will, under reasonable circumstances, have much longer life than mica insulated elements.

In the accompanying drawings,

Fig. 1 is a view in vertical cross-section of a flat iron embodying our invention;

Fig. 2 is a side view of a supporting member for terminal members and the thermally-actuable switch employed in the device illustrated in Fig. 1;

Fig. 3 is a plan view of the supporting member illustrated in Fig. 2;

Fig. 4 is a plan view of the top casting, embodying our invention;

Fig. 5 is a view in vertical section taken on the line V—V of Fig. 4; and

Fig. 6 is a view in vertical section taken on the line VI—VI of Fig. 4.

Referring more particularly to Fig. 1, an electric flat iron 11 comprises a body portion 12, a supporting member 13 and a cover member 14. The cover member 14 is attached to the body member 12 by a bolt 15 and encloses the top portion of the body member 12 and the supporting member 13 therein.

The body portion 12 comprises a sole plate 16, and a top plate 17 secured thereto by bolts 18 and 19, which extend through the top member 17 and into the sole plate 16, and nuts 18a and 20.

The sole plate 16 has a polished bottom surface 21, a bevelled edge 22 and a ground top surface 23. Holes 24 and 25 are drilled and tapped in the sole plate 16 from the surface 23 to receive bolts 18 and 19.

The top plate 17 has an annular groove 28 in the bottom surface thereof which makes substantially a complete turn around its outer periphery and an opening 20 in its rear central portion wherein the member 13 is located. A heating element 26 comprises an electric resistor 29 which is encased in a tube or helix 30 of oxidizable metal such as magnesium. The encased resistor element 29 is located in the groove 28.

The top casting 17 with the magnesium metal tube 30, which encloses the resistor 29 located in the groove 27 is exposed to steam at a high pressure according to the method described in United States Letters Patent No. 1,451,755, issued to C. B. Backer on April 17, 1923 whereby the magnesium metal 30 is changed to magnesium oxide.

The magnesium metal, as it is oxidized, expands substantially to 200% of its original volume. The heating element is compacted by the resulting oxide, to effect a high thermally-conductive relation between the conductor 29 and the top plate 17. The magnesium oxide 30 is of a crystalline structure which extends radially from the resistor 29, and provides an excellent heat path therefrom to the base plate 24. By reason of the efficient thermally-conductive path between the conductor 29 and the base plate 17, the resistor element 29 may be operated at a much lower temperature because the temperature gradients between the conductor 28, oxide 29 and the base plate 16 are materially reduced.

Since the heating unit 26 is treated in its operative position within the top plate 17, the base plate 16 may be polished and finished for assembly without marring the polished surface as would obviously result if the heating element 26 were located in the base plate 16. Obviously, it would be very difficult to treat the magnesium oxide covered conductor 29 in place in the base plate 16 before said base plate has been nickel-plated or polished because of the damaging effect of the acid solutions employed in the electro-plating processes.

The ends of the resistor 29 are brought upwardly through openings 31 and 32 in the top casting 17 illustrated in Fig. 4. One end of the resistor 29, which passes through the opening 32, is connected to a terminal 33 of a thermostat 34 which is supported by the member 13. From a second terminal, not shown, of the thermostat 34 a connection is made to terminal 35. The other end of the resistor 29, which passes through the opening 31, is connected to a second terminal similar to terminal 35 but which is not shown in the drawings.

The supporting member 13 is of substantially L-shape, and serves as a support for the terminals 35, only one of which is shown, and also serves to support the thermostat 34 in its operative position, as illustrated in Fig. 1.

Openings 37 and 38 are provided in a short leg 39 of the member 13, wherein the terminals 35 are supported and held firmly in position by a circular integral lug 41 on the terminals 35 and nuts 40. The terminals are insulated from the member 13 by insulating washers 40a of mica. An opening 42 is provided in the member 13 to permit the bolt 19 to pass therethrough. The member 13 is held firmly in place by the bolt 19 and a nut 20. The thermostat 34 is supported from the member 13 by a bolt 43 located in an opening 44 thereof, and secured thereto by a washer 46 and a nut 47. A pair of openings 48 and 49 are provided in the member 13 whereby the terminals 33 of the thermostat 34 may be located in position in order that the resistor 29

may be connected thereto. A depending lug 50 of the L-shape member 13 prevents said member from bending downwardly so that the thermostat 34 will not touch the sole plate 16.

A thermally responsive member 51 of the thermostat 34 is located nearest the sole plate 16 in order that it may be subjected to substantially the temperature existing at the surface 21 of said sole plate. The supporting member 13 is secured to the top plate 24 by the bolt 19.

The thermostat 34 which we propose to use is described in U. S. Letters Patent No. 1,448,240 issued to J. A. Spencer on March 13, 1923.

The cover member 14, as illustrated in Fig. 1, has a handle portion 52 attached thereto by supporting straps 53 and 54. The straps 53 and 54 are secured to the handle by bolts, not shown, and to the cover 14 by rivets 55 and 56. An opening in the rear portion of the cover member 14 permits the terminals 35 to extend outwardly therefrom, whereby an electrical connection may be effected to an electric power supply.

By means of our invention, we have provided an electrically heated iron which comprises a sole plate, that may be finished and polished independently of the heating unit, a means for heating the aforesaid sole plate, a thermally-actuable switch for controlling the temperature of the sole plate, and a cover member for enclosing the body portion, the heating means, and the thermally-actuable switch. The heating means comprises substantially a cast iron member having a groove in its lower surface wherein a heating element is located and insulated therefrom by an oxidizable material such as magnesium.

The heating means provided in the device embodying our invention may be treated in an autoclave as described in the United States Letters Patent No. 1,451,755 issued to C. B. Backer on April 17, 1923. Since the heating member is treated independently of the sole plate and since the heating unit lends itself to quantity production, we have provided an iron which may be easily repaired or easily assembled, as the case may be, because of the simplicity of the heating unit.

Obviously other modifications and changes in the device illustrated in the drawings embodying our invention may be made without departing from the spirit and scope thereof. We therefore desire that only such limitations shall be placed thereon as shall be imposed by the prior art.

We claim as our invention:

In an electrically heated iron, the combination with a body portion comprising a top casting having a groove therein, a sole plate, a heating element located in the groove in said top casting, terminal pins for the heating element, and a thermally actuable control switch

responsive to the temperature of the sole plate, of a single member of substantially L-shape for supporting said thermally responsive control switch and terminal pins, and 5 means for securing said member of L-shape on the body portion.

In testimony whereof, we have hereunto subscribed our names this 27th day of Nov., 1925.
